Primary Examiner — Paula Allen Greene*(74) Attorney, Agent, or Firm* — Haug Partners LLP**CLAIM**

The ornamental design for a pair of headphones, as shown and described.

DESCRIPTION

- FIG. 1 is a front view of a pair of headphones in accordance with an embodiment of the invention;
FIG. 2 is a right side view of the pair of headphones in accordance with the embodiment of the invention.
FIG. 3 is a left side view of the pair of headphones in accordance with the embodiment of the invention.
FIG. 4 is a top side view of the pair of headphones in accordance with the embodiment of the invention.
FIG. 5 is a bottom side view of the pair of headphones in accordance with the embodiment of the invention.
FIG. 6 is a rear view of the pair of headphones in accordance with the embodiment of the invention; and,
FIG. 7 is a perspective view of the pair of headphones in accordance with the embodiment of the invention.
